WELL PUMP

Emery C. Furrer, near Frankfort, Ill.

Application May 26, 1955, Serial No. 511,315

12 Claims. (Cl. 103—46)

This invention relates to improvements in well pumping apparatus, and particularly to such apparatus for use in oil wells.

One object of the invention is to provide an improved pumping apparatus for use in an oil well for pumping oil from the well which comprises a pump and a pump actuating motor that are lowered into a well casing within pumping range of the oil therein and which motor is actuated by a column of oil under pressure, the pressure being supplied by a source of power at the surface. The pumping apparatus in the well comprises a pump which is actuated by a reciprocating, fluid-pressure-actuated motor, and both are suspended within the well casing at or near the bottom of the well by two pipe lines, one of which lines conveys oil from a power source at the surface for actuating the fluid actuated motor which operates the oil pump, and the other of which receives the oil from the pump as well as the exhaust oil from the motor and delivers it from the well. A portion of the oil recovered from the well is used as the pressure fluid for actuating the pump motor within the well during the operation of the apparatus.

Another object of the invention relates to the provision of a reciprocal motor which is actuatable by fluid pressure and which effects actuation of a pump, the motor mechanism comprising a piston to which a pump plunger is connected for actuation, the reciprocal piston of the motor being provided with a shiftable sleeve which delivers pressure fluid selectively to pressure chambers in the pump casing at the ends of the piston for effecting actuation of the piston, and which sleeve is shiftable within the piston during the terminal portion of each stroke thereof for cushioning the terminal portions of the strokes and for reversing the direction of operation of the piston.

Still another object of the invention is to provide a novel reciprocating motor which is actuated solely by a continuous flow of fluid into the motor.

A further object of the invention is the provision of a new and improved reciprocating motor which is actuated by a single pressure fluid attachment to the motor with a means within said motor to reverse the fluid flow to effect the reciprocal movement of the motor.

A still further object of the invention is to provide a novel compact reciprocal pump that will pump fluid upwardly on both the upward and downward stroke of the pump piston.

Numerous other objects and advantages of the invention will be apparent as it is better understood from the following description, which, when taken in connection with the accompanying drawings, disclose a preferred embodiment thereof.

In the drawings:

Figure 1 is a broken elevational view of a pumping apparatus embodying the invention in position in the casing of an oil well;

Fig. 2 is an enlarged vertical section on line 2—2 of Fig. 1 illustrating the fluid motor and pump;

Fig. 3 is a plan view of the fluid motor and pump casting as viewed on line 3—3 of Fig. 2;

2

Fig. 4 is a horizontal sectional view taken on line 4—4 of Fig. 2 and illustrating the two chambers of the pump and the two oil delivery ducts or passages communicating therewith;

5 Fig. 5 is a broken vertical sectional view taken on line 5—5 of Fig. 4;

Fig. 6 is a transverse sectional view of the motor piston taken on line 6—6 of Fig. 2 as viewed in the direction of the arrows;

10 Fig. 7 is a horizontal sectional view of the motor piston taken on line 7—7 of Fig. 2;

Fig. 8 is a vertical sectional view in the form of a development taken along the lines 8—8 of Figs. 6 and 7 to illustrate in a single view the relation of the sleeve valve of the motor piston to the intake duct of the actuating pressure fluid line and the exhaust line;

15 Figs. 9, 10, and 11 are broken vertical developed sectional views of the fluid motor during final positions of the up-stroke of the piston showing the path of flow of pressure fluid to the lower pressure chamber below the piston and the paths for the exhaust of fluid from the upper pressure chamber;

20 Fig. 12 is a similar view showing the relationship of the piston, sleeve valve and parts at the end of the up-stroke;

25 Fig. 13 is a view similar to Figs. 9—12 but showing the sleeve valve actuated from the position of Fig. 12 to a reverse position for directing actuating fluid above the piston to effectuate the down-stroke thereof; and

30 Fig. 14 is a horizontal sectional view of the sleeve valve keying means taken on line 14—14 of Fig. 2.

Generally, one embodiment of the invention consists of a pressure and discharge means A, a motor B and a pump C (Fig. 1). When fluid pressure is applied from 35 the fluid and discharge means A to the motor B, the pump C, through a common connection, will be actuated to pump fluid upwardly. The fluid pumped upwardly by pump C will return up through motor B's discharge system and then up through the discharge means of fluid 40 pressure and discharge means A.

In Figure 1, the improved pumping apparatus is illustrated in operative position within a casing 14 of a well. In said figure, an electrical motor 15 is shown for operating a pump 16 which forces oil through a pipe 17 down into the well, and the pipe 17 is connected to the upper end of a fluid motor casing 18. To the lower end of the casing 18 is connected a pump casing 19 from which into casing 18 the pump discharges oil which passes from the upper end of casing 18 into a delivery pipe 21 which conveys the oil to a tank 22 at the surface. From this tank 22 the pump 16 draws oil through pipe 23 which is forced under pressure into the pipe 17. The pipe 21 is of greater diameter than pipe 17 inasmuch as the pressure fluid which passes down through pipe 17 to actuate the fluid motor which activates the pump, is exhausted into the pipe 21 which also carries the ground oil or petroleum discharged from the pump.

In Fig. 1, a pipe section 24 is shown extending from the lower end of the pump casing 19 and is provided with 50 a sieve 25 at the lower end for excluding extraneous substances from the petroleum or ground oil drawn into the pipe by the suction of the pump in casing 19. Actually the ground oil in the well may be at a level substantially above the sieve 25, in fact the normal level 55 of the oil (petroleum) in the well may be at such height as to immerse the casing sections 18 and 19 or partially so.

By the operation of the electrical motor 15, the pump 16 is actuated to draw oil from the tank 22 and force it down the pressure pipe 17. Normally both pipes 17 and 21 will be filled with oil and the columns of oil in the pipes, being of substantially equal height, will exert a

similar pressure per square inch at the lower ends. In other words, the two columns of oil will be in balance, normally, and pump 16 need supply oil to the line 17 only at a suitable pressure for actuating the pump motor within the well. Thus, if the per square inch pressure of the two columns of oil in the pipe lines 17 and 21 is 1,000 lbs., for example, the pump 16 should deliver oil to line 17 at from 1,000 to 1,200 lbs. per square inch for procuring efficient operation of the pump motor within the well and the discharge of oil from the exhaust line 21. It will be appreciated that where the well is deeper and the static pressure of the two columns of oil in lines 17 and 21 are greater, increased pressure of oil delivered to the line 17 by pump 16 may be required.

As shown in Fig. 2 and Fig. 8, the casing 18 has an upper header 26 and a common lower header 27. This forms an upper casing chamber 28. The pressure oil line 17 and oil discharge line 21 are rigidly secured to header 26. Within upper casing chamber 28 is slidably mounted a motor piston 29, having piston rings 30. Secured at the upper end of this motor piston are an oil pressure sleeve 31 and an oil discharge sleeve 32. As shown in Fig. 8, these sleeves are slidable through header 26 and pipes 17 and 21. Communicating with pressure sleeve 31 is a pressure passage 33 which extends longitudinally within motor piston 29. Communicating with discharge sleeve 32 is a discharge passage 34 which extends longitudinally within motor piston 29. Also within motor piston 29 is a valve passage 35 which is eccentric to the axis of piston 29, extends completely through motor piston 29 and is parallel with pressure passage 33 and discharge passage 34. Pressure passage 33 is connected with valve passage 35 at 36, whereas discharge passage 34 is connected with valve passage 35 at 37 and 38. Reciprocally mounted within valve passage 35 is a valve sleeve 39. This valve sleeve has fixedly mounted at either end two flange stops 41 and 42. As will be explained later, flange stop 42 is keyed so as to prevent rotation of sleeve 39 with respect to motor piston 29. Valve sleeve 39 has a partition 43 dividing the valve sleeve 39 into upper and lower sleeve chambers 44 and 45. The upper sleeve chamber 44 has a pressure port 46, a discharge port 47 and a discharge bypass port 48. On the outer surface and adjacent the upper end of valve sleeve 39 is a discharge bypass recess 49. The lower valve sleeve chamber 45 has a pressure port 51, a discharge port 52 and a discharge bypass port 53. On its outer surface and adjacent the lower end of valve sleeve 39 is a discharge recess 54. As can be seen, the motor piston 29 divides the upper casing chamber 28 into an upper motor chamber 55 and a lower motor chamber 56. The upper header 26 has a recess 57 in its lower surface, and the common header 27 has a similar recess 58 in its upper surface. These recesses 57, 58 are employed to accommodate the ends of valve sleeve 39, and their function will be explained later.

Viewing Fig. 8, the motor piston 29 is shown in its midposition with fluid under pressure coming through pressure passage 33 into lower sleeve chamber 45 and then into lower motor chamber 56. In this position, valve sleeve 39 will be kept in its uppermost position by fluid pressure applied to partition 43 in sleeve 39. In this position, fluid under pressure will be forced into the lower motor chamber 56, and fluid will be forced from upper motor chamber 55 through upper sleeve chamber 44, port 47 and into discharge passage 34. As a result, fluid pressure applied through pipe 17 and pressure passage 33 will force motor piston 29 upwardly so long as valve sleeve 39 remains in this uppermost position. The uppermost position of valve sleeve 39 is also shown in Fig. 9 at the moment that valve sleeve 39 is in full engagement with recess 57. From this point on, valve sleeve 39 remains fixed with relation to header 26 while motor piston 29 continues movement upwardly relative

to header 26. This movement continues by virtue of pressure port 51 being open, with the discharge from upper motor chamber 55 going through upper bypass port 48 through port 47 and then upwardly through discharge passage 34. As can be seen, as motor piston 29 continues its movement upwardly, the pressure passage through port 51 and the discharge through bypass port 48 are decreasing.

When the motor piston 29 in its upward movement reaches a position as shown in Fig. 10, the pressure fluid going into lower motor chamber 56 continues its flow through port 51, although the amount of flow has been greatly decreased by partition 43 substantially blocking outlet 36. On the other hand, the discharge from upper motor chamber 55 then goes solely through discharge bypass recess 49, since bypass port 48 has at this point been fully covered by motor piston 29 due to its upward travel.

By virtue of the above conditions, the motor piston 29 will continue its travel upwardly until reaching the position shown in Fig. 11. At this point, fluid discharge from upper sleeve chamber 44 is completely blocked, with pressure fluid entering through a small opening in port 46. Consequently, the pressure in the upper sleeve chamber 44 is much greater than the pressure in sleeve chamber 45, since lower motor chamber 56, receiving fluid through a small opening in port 51, can discharge its fluid through lower discharge bypass recess 54. Due to this, and also a venturi action caused by rapid fluid flow into lower sleeve chamber 45, the valve sleeve 39 will be lowered to the position as shown in Fig. 12.

In the position as shown in Fig. 12, which is reached due to the action disclosed in the previous paragraph, the fluid pressure from pressure passage 33 will then enter upper sleeve chamber 44 only through a small opening in upper pressure port 46. Since the upper sleeve chamber 44 at this time has no discharge, the valve sleeve 39 will continue its movement downwardly relative to motor piston 29, because of fluid pressure upon partition 43, until it reaches a position as shown in Fig. 13.

When the valve sleeve 39 reaches the position as shown in Fig. 13, the fluid pressure through pressure passage 33 will be received solely by upper motor chamber 55. This will cause motor piston 29 to move downwardly. This force causing motor piston 29 to move downwardly will force the fluid in lower motor chamber 56 upwardly through lower sleeve chamber 45, port 52 and upwardly through discharge passage 34.

As can be seen, the motor piston 29 will continue its downward travel until valve sleeve 39 engages recess 58. At this point, the flow of pressure fluid through pressure passage 33 will be reversed upwardly by the same sequence of events which have been previously described and the motor piston 29 will then be forced upwardly.

As shown in Fig. 2, the connecting pipe 58 is slidable through an aperture in common header 27 having sealing rings 20. The upper portion of connecting pipe 58 is rigidly connected to motor piston 29. Connecting pipe 58 communicates with discharge passage 34 through connecting passage 60 (Figs. 2 and 7). As shown in Fig. 14, stop flange 42, mounted on valve sleeve 39, is keyed to connecting pipe 58 by virtue of keying recess 59 in a laterally extended portion of the flange slidably engaging the pipe. This, of course, will prevent rotation of valve sleeve 39 and will insure its proper operation.

Casing 19 forms a lower casing chamber 61 (Fig. 2) with common header 27 at one end and a lower header 62 at the other end. Connecting rod 58 is rigidly connected at its lower end to a pump piston 63. The pump piston 63 consists of a circular body portion 64 with an upper piston plate 65 and a lower piston plate 66. The plates 65 and 66 are secured to the circular body portion 64 through some suitable means such as bolts 67. Secured between plates 65 and 66 and circular body portion 64 are

gaskets 68 made of leather or some other suitable material. As can be seen in Fig. 2, connecting pipe 58 is rigidly secured to upper plate 65 by a threaded connection. Similarly secured to plate 66 is a pump pipe 69 which is slidable through an aperture in header 62 having sealing rings 70, and enters into pipe 24 giving access to the fluid to be pumped upwardly through sieve 25. The interior of the pump piston consists of an upper piston chamber 71 and a lower piston chamber 72. Extending between these two chambers are piston passages 73 and 74. Within each of these passages are two check valves 75, 76, and 77, 78, respectively. The placement of these check valves form an intermediate piston chamber 79 in passage 73 and an intermediate piston chamber 81 in passage 74. Pump piston 63 divides lower casing chamber 61 into upper pump chamber 82 and lower chamber 83. Intermediate piston chamber 79 is connected to a laterally extending pump passage 84 which is in turn connected to a downwardly extending pump passage 85 (Fig. 4). Passage 85, as shown in Fig. 5, extends through piston plate 66, thus affording a direct communication between intermediate piston chamber 79 and lower pump chamber 83. Intermediate chamber 81 is connected to a laterally extending pump passage 86 (Fig. 4) which is in turn connected to an upwardly extending pump passage 87. Pump passage 87, as shown in Fig. 5, extends upwardly through plate 65 and, consequently, affords a direct communication between upper pump chamber 82 and intermediate piston chamber 81.

In the operation of the pump, the connecting pipe 58 is given a reciprocating motion by the operation of the motor, as described above. This motion in turn is communicated directly to the pump piston 63, because connecting pipe 58 is rigidly connected to pump piston 63. As the pump piston travels upwardly from the position shown in Fig. 2, the fluid in upper pump chamber 82 is forced downwardly through passages 87 and 86 and into intermediate chamber 81. The pressure of the fluid in intermediate chamber 81 will hold check valve 78 closed and, consequently, the fluid will travel upwardly through check valve 77, upper piston chamber 71, connecting pipe 58, then through discharge passage 34 and eventually into tank 22. The pressure from the fluid going through upper piston chamber 71 will hold check valve 75 closed. At the same time that fluid is being forced in this manner from upper piston chamber 82 upwardly through connecting pipe 58, lower pump chamber 83 is enlarging and thus drawing fluid downwardly from intermediate chamber 79 by way of passages 84 and 85. Since check valves 75 and 78 are held closed due to the fluid being drawn from upper pump chamber 82 into connecting pipe 58, the drawing of fluid into lower pump chamber 83 will open check valve 76 and draw the fluid in pumping pipe 69 (and pipe 24) through lower piston chamber 72, past check valve 76, through passages 84 and 85 and into lower pump chamber 83. Thus it is seen when the pump piston travels upwardly two actions occur simultaneously. Fluid in upper pump chamber 82 is pumped up through connecting pipe 58 and fluid in pumping pipe 69 is drawn into lower pump chamber 83.

When motor piston 29 reverses its travel and moves downwardly due to the action of valve sleeve 39 is previously described, pump piston 63 will also reverse its travel and move downwardly. When this occurs, lower pump chamber 83 will be made smaller and consequently fluid will be forced from pump chamber 83 through passages 85 and 84 into intermediate piston chamber 79. At this point, the fluid pressure will force check valve 76 closed and will travel upwardly through check valve 75, upper piston chamber 71, into connecting pipe 58 and eventually through discharge passage 34 into tank 22. This fluid flow will cause check valve 77 to stay closed. At the same time that this fluid action is occurring, upper pump chamber 82 is enlarging, causing the fluid in pumping pipe 69 (and pipe 24) to be drawn upwardly through

lower piston chamber 72, past check valve 78 (check valve 76 being forced closed), into intermediate piston chamber 81. Since check valve 77 is forced closed the fluid will then travel through passages 86, 87 and into upper pumping chamber 82. Thus it is seen that on the downward stroke of pump piston 63, fluid in lower pump chamber 83 is forced up through connecting pipe 58, while fluid in pipes 69 and 24 is drawn into upper pump chamber 82. Hence on both upward and downward strokes of pump piston 63, fluid is pumped from one of the pump chambers upwardly through connecting pipe 58 while simultaneously the fluid in pumping pipe 69 is drawn into the other pumping chamber. Thus is disclosed a highly efficient double-acting pump.

15 It is thought that the invention and many of its attendant advantages will be understood from the foregoing description, and it will be apparent that various changes may be made in the form, construction and arrangement of the parts without departing from the spirit 20 and the scope of the invention or sacrificing all of its material advantages, the form hereinbefore described being merely a preferred embodiment thereof.

I claim:

1. A well pump, comprising an upper casing chamber 25 and a lower casing chamber; a fluid motor in said upper casing chamber comprising a motor piston having a fluid pressure passage, a fluid discharge passage, and a single valve passage therein communicating with both said pressure and discharge passages, and a unitary sleeve valve 30 mounted for limited reciprocal movement in said valve passage to control the direction of flow of fluid delivered under pressure from said pressure passage alternately to opposite ends of said motor piston and also from the others of said opposite ends alternately to said discharge 35 passage to actuate said piston for reciprocal movement within said upper chamber; a reciprocating, double-acting pump within said lower casing chamber comprising a pump piston having fluid passages therethrough, ball valves controlling the flow of fluid through said passages, 40 and a pumping pipe connected to said pump piston for receiving fluid to be pumped upwardly, and a connecting pipe interconnecting said pump piston and said motor piston for reciprocating the pump piston and conducting the fluid discharge of said pump to said fluid discharge passage of said motor.
- 45 2. A well pump, comprising a casing divided into upper and lower casing chambers, a motor in said upper casing chamber comprising a motor piston actuated for reciprocal movement by fluid pressure, a fluid pressure supply 50 pipe and a fluid discharge pipe connected to the upper end of said casing, fluid discharge means extending through said motor piston and communicating with said discharge pipe, a reciprocating, double-acting pump in said lower casing chamber, said pump having a pumping pipe for receiving fluid to be pumped upwardly, and a connecting pipe connecting said pump to said motor piston for reciprocal movement, said connecting pipe connecting the discharge of said pump to said fluid discharge means.
- 55 3. A well pump, comprising a casing divided into an upper and a lower casing chamber, a motor in said upper casing chamber comprising a piston actuated for reciprocal movement by fluid pressure, a fluid pressure passage and a fluid discharge passage within said piston, a fluid pressure means connected to said fluid pressure passage and a fluid discharge means connected to said fluid discharge passage, a single sleeve valve mounted for reciprocal movement relative to said motor piston to alternately direct said fluid pressure to the upper and lower surfaces of said motor piston and connect said fluid discharge passage with opposite ends of said upper casing chamber to automatically effect continuous reciprocating movement of said motor piston, a reciprocal pump in said lower chamber, said pump having a pumping pipe for receiving fluid to be pumped upwardly, and a connecting pipe connecting 60 said pump to said motor piston and connecting the dis-
- 65
- 70
- 75

charge of said pump to said fluid discharge passage of said motor piston.

4. A well pump as set forth in claim 3, wherein said sleeve valve is mounted for reciprocal movement in said motor piston eccentric to the axis thereof.

5. A well pump, comprising a casing having an upper casing chamber with an upper header at one end and a common header at the other end, a motor in said upper chamber comprising a motor piston dividing said upper casing chamber into an upper and a lower motor chamber, fluid pressure means for applying fluid pressure and fluid discharge means for discharging said fluid pressure mounted on said upper header to actuate said motor piston for reciprocal movement within said upper casing chamber, a fluid pressure passage and a fluid discharge passage within said motor piston, means for establishing communication between said fluid pressure passage and said fluid pressure means and said fluid discharge passage and said fluid discharge means, a valve passage extending within said motor piston and communicating with said pressure passage at one point and communicating with said discharge passage at two points, a valve sleeve mounted for reciprocal movement relative to said motor piston in said valve passage, a sleeve partition dividing said sleeve into an upper and a lower sleeve chamber, an upper pressure port, an upper discharge port and an upper discharge bypass means in said upper sleeve chamber, a lower pressure port, a lower discharge port and a lower discharge bypass means in said lower sleeve chamber, said pressure ports communicating with said pressure passage, said discharge ports communicating with said discharge passages and said discharge bypasses, and means communicating with said upper and lower motor chambers and said fluid discharge means in such a sequence, due to the application of pressure by said fluid pressure means and the abutment of said sleeve with the ends of said upper casing chamber, as to automatically reverse the flow of the pressure fluid from one motor chamber to the other.

6. A well pump as set forth in claim 5, wherein said upper discharge bypass means comprises an upper bypass port in said sleeve and an upper bypass recess on the exterior of said sleeve, and said lower discharge bypass means comprises a lower bypass port in said sleeve and a lower bypass recess on the exterior of said sleeve.

7. A well pump as set forth in claim 5, wherein said upper discharge bypass means comprises an upper bypass port in the upper sleeve chamber that in certain positions communicates with the upper motor chamber, and an upper bypass recess on the exterior of said sleeve that in certain positions affords communication between said upper motor chamber and said discharge passage, while the lower discharge bypass means comprises a lower bypass port in the lower sleeve chamber that in certain positions communicates with the lower motor chamber, and a lower bypass recess on the exterior of said sleeve that in certain positions affords communication between said lower motor chamber and said discharge passage.

8. A well pump as set forth in claim 5, wherein said casing has a lower casing chamber with said common header at one end and a lower header at the other end, a pump in said lower casing chamber comprising a pump piston dividing said lower casing chamber into upper and lower pump chambers, said pump piston having an upper and lower piston chamber, said pump piston being rigidly connected with said motor piston by a connecting pipe slidably mounted in said common header and connecting said upper pump chamber with said fluid discharge passage, a hollow pumping pipe slidably in said lower header and rigidly connected to the lower portion of said pumping piston, thereby affording communication between said lower pump chamber and the outside of said casing, first and second pumping passages between said upper and lower piston chambers, and two check valves in each of said pumping passages forming two intermediate pumping chambers, one of said intermediate pumping cham-

bers being in communication with said upper pumping chamber and the other intermediate pumping chamber being in communication with said lower pumping chamber.

5 9. In a well pump, a fluid motor comprising a casing chamber, a motor piston mounted for reciprocal movement within said chamber and dividing said casing chamber into upper and lower motor chambers, fluid pressure means and fluid discharge means, and a valve sleeve 10 mounted for reciprocal movement in said motor piston, said valve sleeve having a pressure port, a discharge port and a discharge bypass means, said pressure port being in registry with said fluid pressure means in certain positions, said discharge port being in registry with said fluid discharge means in certain positions, and said discharge bypass means affording communication between one of 15 said motor chambers and said discharge bypass means in certain positions, said fluid pressure means actuating said sleeve so as to reverse the flow of said pressure means from one end of said motor piston to the other to effect a reciprocal movement of said motor piston.

10 10. A fluid motor as forth in claim 9, wherein said discharge bypass means comprises a bypass recess on the exterior of said sleeve and a bypass port through said sleeve.

15 11. For use in a well bore, a pump comprising a casing adapted to be disposed adjacent the lower end of said bore, means dividing the interior of said casing into an upper motor chamber and a lower pump chamber, a 20 double-acting pump disposed in said pump chamber, a motor piston disposed in said motor chamber and having a fluid supply passage, a separate fluid discharge passage, and a valve passage extending therethrough, with said valve passage interconnecting said supply and discharge passages, a pipe interconnecting said pump and said piston for imparting movement of the latter to said pump and transmitting fluid discharge from said pump to said discharge passage, a supply pipe extending down said bore and connected at its lower end to the upper 25 end of said casing for supplying fluid under pressure, means interconnecting said supply pipe and said supply passage, a discharge pipe of larger diameter than said supply pipe extending down said bore and connected at its lower end to the upper end of said casing, means interconnecting said discharge pipe and said discharge passage, and a sleeve valve mounted in said valve passage to block communication between said supply and discharge passages and reciprocable to alternately first direct fluid from said supply passage into said motor chamber below said piston and to connect said motor chamber above said piston with said discharge passage and, second, to direct fluid from said supply passage into said motor chamber above said piston and connect said motor chamber below said piston with said discharge passage, whereby to effect reciprocal movement of said piston.

30 12. A pump according to claim 11, wherein said sleeve valve is provided with a central partition of slightly less thickness than the vertical dimension of the interconnection between said fluid supply and valve passages, and ports in said valve directly above and below said partition, whereby a Venturi action is effected during each relative reciprocation between said valve and said piston to insure reversal of movement of the latter.
